UNITED STATES PATENT OFFICE

146,383

DESIGN FOR A SEWING MACHINE CABINET

Joseph L. Ray, Darien, Conn., assignor to The
Singer Manufacturing Company, Elizabeth,
N. J., a corporation of New Jersey

Application December 22, 1945, Serial No. 125,000

Term of patent 14 years

(Cl. D33—12)

To all whom it may concern:

Be it known that I, Joseph L. Ray, a citizen of the United States, residing at Darien, in the county of Fairfield and State of Connecticut, have invented a new, original, and ornamental Design for a Sewing Machine Cabinet, of which the following is a specification, reference being had to the accompanying drawing, forming a part thereof.

The figure is a perspective view of a sewing machine cabinet showing my new design.

The top of the cabinet is of oval shape and the side not shown is the same as the one illustrated, except that the rear panel is plain.

I claim:

The ornamental design for a sewing machine cabinet, as shown and described.

JOSEPH L. RAY.
